Specification for Design.

Patented Oct. 15, 1918.

Application filed July 8, 1918. Serial No. 243,966. Term of patent 14 years.

To all whom it may concern:

Be it known that I, JOHN P. HOTZ, a subject of the Emperor of Austria, residing at Watertown, in the county of Middlesex and State of Massachusetts, have invented a certain new, original, and ornamental Design for a Fan and Clock Case, of which the following is a specification, reference being had to the accompanying drawing, forming part thereof.

In the drawings:

Figure 1 is a front elevation of a fan and clock case showing my new design.

Copies of this patent may be obtained for five cents each, by addressing the "Commissioner of Patents, Washington, D. C."

Fig. 2 is a plan view of the same.

I claim—

The ornamental design for a fan and clock case as shown.

In testimony whereof I have hereunto set my hand in presence of two subscribing witnesses.

JOHN P. HOTZ.
